INVENTOR,

Joseph Linhart,

BY

James P. Dubameel.

ATTORNEY

UNITED STATES PATENT OFFICE.

JOSEPH LINHART, OF ELMHURST, NEW YORK.

GARMENT-FASTENER.

1,301,855.

Specification of Letters Patent. Patented Apr. 29, 1919.

Application filed April 18, 1918. Serial No. 229,243.

To all whom it may concern:

Be it known that I, JOSEPH LINHART, a citizen of the United States, and resident of Elmhurst, in the county of Queens and State 5 of New York, have invented certain new and useful Improvements in Garment-Fasteners, of which the following is a specification.

This invention relates to hooks and fasteners and especially to what is commonly known as hooks and eyes and its object is to overcome the objectionable features in the means for securing these articles to cloth or fabric by combining with them a point to 10 penetrate the said fabric and a spur to enter the same when the two members of the fastener are to be attached to a garment. These and other details and objects of the invention are more fully described in the following specification, set forth in the claims and 15 illustrated in the accompanying drawings, wherein:

Figure 1 is a perspective view of the two fasteners detached but in position to be 20 united.

Fig. 2 is a longitudinal sectional view through the hook and eye while secured to two parts of a garment to unite them and on line 2—2 of Fig. 3.

Fig. 3 is a plan view of the same.

As shown in the drawings the eye-member 5 is preferably formed with a head 6 at its outer end and a slot 7 provided therein for the reception of the hook 10 of the co-operating member 8, the exposed parts of 25 the two members consisting of, otherwise, strips of sheet metal of uniform width and at their inner ends turned under as at the shoulder 9 and the under portion tapered to 30 a point 11 which is used to penetrate and be located under the fabric of a garment.

The two members are made so that the upper parts and the points are deflected, the latter being at a distance from the hook or 35 eye so that the point may be easily inserted in the fabric up to the shoulder 9 and the two parts pressed together so that these parts are substantially parallel. It is customary to connect the hooks and eyes with

the garment at its meeting edges 12 and 13 50 and the two members are reversed and attached to opposite sides of the edges as shown in Fig. 2 so that the hook is secured to the under side of the fabric while the eye is on the outer side and the parts of each 55 member are closed and besides being held by the pin 11 a small spur 15 is provided and punched from the body parts 5 and 8 and passes through the fabric and into a perforation 16 near the upper end of the 60 pin and the spur may be long enough to be turned back after passing through the hole so as to clamp the parts together.

This means of fastening the members assures a strong and safe connection between 65 each member and the fabric and a connection that is quickly made.

As the parts of the fasteners are small and fragile additional strength may be given them at points where the most strain is put 70 upon them by forming ribs 17 in the upper part or body of each member.

While the old type of hook and eye is sewed in place with considerable time and trouble and the threads are very liable to 75 break or be pulled off, thereby releasing the fastener, this improvement is quickly and substantially located and is able to withstand far more strain than the old style hook and eye.

It is obvious that the device may be otherwise constructed or modified without departing from the essential features above described or from the scope of the appended 80 claims.

What I claim as new is:

1. In garment fasteners, the combination of co-operating parts one having a hook and the other a socket or eye, pins at the opposite ends of the hook and socket, shoulders 90 at the upper ends of the pins, and spurs to engage the garment when the fasteners are located.

2. In garment fasteners, the combination of ribbed plates having at one end a fastening means and at the other end a shoulder, a reduced and tapered part extending from the shoulder turned substantially parallel 95

with the plate and having a perforation, and a spur from the plate and adapted to enter the perforation.

3. In a garment fastener, the combination of a ribbed plate having fastening means at one end and a shoulder at the other, a tapering pin extending from the shoulder with a perforation and adapted to enter a fabric as

far as the shoulder, and a spur from the plate adapted to enter the perforation when 10 the plate and pin are pressed together.

Signed at New York, in the county of New York and State of New York, this 1st day of April A. D. 1918.

JOSEPH LINHART.
